FUEL METERING AND FEEDING DEVICE

Filed May 2, 1921

UNITED STATES PATENT OFFICE

EZEKIEL FIELD WHITE, OF CHICAGO, ILLINOIS

FUEL METERING AND FEEDING DEVICE

Application filed May 2, 1921. Serial No. 466,348.

This invention relates to a fuel metering and feeding device.

One object of the invention is to provide a simple, efficient and durable device which is capable of accurately metering and feeding fuel in an improved manner whereby the fed fuel is vaporized and prepared for complete combustion upon being mixed with the proper amount of air.

10 Another object is to provide an improved metering and feeding device which is particularly adapted for efficient use in connection with low grade oils.

These and other objects are accomplished 15 by means of the device shown on the accompanying sheet of drawings, the single figure showing the device proper in a vertical longitudinal sectional view.

The various novel features of my invention will be apparent from the following description and drawings and will be particularly pointed out in the appended claims.

Referring to the drawings, it will be noted that the device includes a casing 10 forming 20 a fuel supply chamber 11, an intermediate chamber 12 and a compression chamber 13, fuel, in this particular embodiment of the invention, being supplied to chamber 11 through a pipe 14, through which oil is forced by a pump 16 which draws the oil 25 through a pipe 15. The plunger of the pump is actuated through a pitman 17 pivotally connected at 18 to a pin mounted on a flange on the shaft 19. The fuel chamber 11 is provided with an overflow pipe 20 which 30 controls the height of the fuel within the chamber. It will be noted that the fuel supply chamber 11 is larger than the intermediate chamber 12 and that the latter is larger 35 than the compression chamber 13.

Slidably mounted in the compression chamber 13 is a stem 21 formed at the lower end of a plunger 22, having an intermediate portion adapted to receive and measure 40 charges of hydrocarbon supplied from the fuel chamber 11 and then transfer same to the intermediate chamber 12. In this particular instance, the measured quantity of hydrocarbon is transferred in circumferential grooves 23 formed in the periphery of

an intermediate portion of the plunger 22. The plunger is reciprocated in a sleeve 24, the latter of which is provided with a plurality of openings 25 forming passageways for hydrocarbon which is transferred from the chamber 11 to a relatively small chamber 26 within the sleeve 24, from which the hydrocarbon is passed directly into the grooves 23 of the plunger. The plunger is reciprocated through a bell crank lever 27, one arm of which is provided with an elongated slot 28 in which a pin 29 on the plunger may move, the other arm 30 of the bell crank lever being actuated in one direction by a cam 31 mounted upon the shaft 19 for raising the plunger. A spring 33 forces the plunger in its downward movement. This spring preferably is mounted in a cup-shaped member 34 at the upper end of the plunger 22 and is provided with a cap 35, the position of which may be changed by threaded means 36 for varying the tension of the spring.

Secured to the lower end of the casing 10 is a nozzle 37 having a passageway 38, which communicates with the compression chamber 13. Adjustably mounted in the nozzle 37 is a valve 39 for controlling the size of the outlet of the nozzle and accordingly the flow of fuel therethrough. The fuel supply chamber is provided with a vent 45 whereby air is supplied to said chamber. An air connection 46 is provided between the fuel supply chamber 11 and intermediate chamber for a purpose to be described later. The main gear 32, shaft 19, cam 31, plunger 22, 50 and pump 16 are driven by a motor 40 through a shaft 41 and a worm 42 meshing with the gear 32. The motor preferably is mounted on a bracket 43 to which all other parts are directly or indirectly connected, thereby 55 forming a compact unitary equipment.

In connection with the operation of the device, it will be understood that when the plunger 22 is raised into a position where the receiving grooves 23 reach the chamber 26, fuel 60 will flow into and fill all exposed grooves, whereupon the spring 33 will forceably drive the plunger 22 downwardly when the tip of arm 30 of the bell crank lever 27 has passed the high spot on cam 31, a measured quan- 65

5 tity of fuel thereby being transferred from the fuel supply chamber 11 to the intermediate chamber 12. The fuel in the grooves 23 thereupon flows downwardly into the bottom of the intermediate chamber 12, and upon the next upward stroke of the plunger 22, an appreciable vacuum, which is formed in the compression chamber, causes the hydrocarbon and some air in intermediate chamber 10 12 to be drawn down into the compression chamber as soon as the stem 21 rises out of the compression chamber 13. Upon the next downward thrust of the plunger 22 and accordingly, the stem 21 into the compression chamber 13, the fuel, a combination of the hydrocarbon and air therein will be compressed to a relatively high degree causing a rise in temperature and a partial vaporization of the latter as it is forceably ejected outwardly 20 through the nozzle 37. This vaporized fuel may be used in any of the many known manners such as in internal combustion engines, fire boxes, etc. Said vaporized fuel when mixed with the proper amount of air forms 25 a combustible mixture which may be efficiently burned. By means of this device, the relatively heavy or crude oils may be efficiently used, and, as a matter of fact, the use of the device is not limited to liquid fuels for the 30 same may be used in connection with powdered and gaseous fuels.

35 The quantity of fuel transferred from the main fuel supply chamber 11 to the intermediate chamber 12, upon each stroke of the plunger 22, is controlled in this case by the number of grooves 23 which are exposed to the chamber 26 associated with fuel supply chamber 11. If it is desired to decrease the measured charge upon each stroke, the same 40 may be accomplished by raising the sleeve 24 by turning the latter in the desired directions, it being noted that the sleeve 24 is threaded in a bushing 44 carried in the upper part of the casing 10. As shown, the 45 sleeve 24 is in one of its limiting positions wherein the maximum measured charge is supplied upon each stroke of the plunger 22.

50 By means of this arrangement, fuels of various descriptions are fed, accurately metered and compressed within the device and discharged therefrom in a partially vaporized state in condition to be mixed with proper proportions of air to form a combustible mixture which may be used in any desired manner.

55 It will be understood that air for forming a part of the fuel mixture which is compressed in compression chamber 13 is admitted first to chamber 11 through the opening 45 and 60 then passes through the connection 46 between chambers 11 and 12 and into the latter chamber. Such air then passes into the compression chamber 13 with the hydrocarbon when the stem 21 is lifted out of chamber 13.

65 It is my intention to cover all modifications

of the invention falling within the spirit and scope of the following claims.

I claim:

1. In a device of the class described, the combination of an oil supply chamber, a compression chamber, and a plunger having means for transferring oil from said fuel chamber towards said compression chamber, said plunger also having a portion operable in said compression chamber, which, when moved outwardly from said compression chamber causes a vacuum which draws the oil mixed with air into said compression chamber preparatory to the mixture being compressed therein by said plunger portion. 70 75

2. In a device of the class described, the combination of an oil supply chamber, an intermediate chamber, a compression chamber, a plunger having portions operable in said chambers, one of said portions for transferring oil from said supply chamber to said intermediate chamber and another of said portions operable in said compression chamber for compressing a mixture including oil transferred from said intermediate chamber to said compression chamber. 80 85

3. In a device of the class described, the combination of an oil supply chamber, an intermediate chamber, a compression chamber, a plunger having portions operable in said chambers, one portion of said plunger having transfer means whereby a measured charge of oil may be transferred from said supply chamber to said intermediate chamber, said plunger having another portion reciprocated in said compression chamber for creating a vacuum therein for drawing air and oil from said intermediate chamber to said compression chamber during one stroke and for compressing the mixture in said compression chamber during another stroke. 100 105

4. In a device of the class described, the combination of an oil supply chamber, an intermediate chamber, a compression chamber, a plunger having portions operable in said chambers, one portion of said plunger having transfer means whereby a measured charge of the oil may be transferred from said supply chamber to said intermediate chamber, said plunger having another portion reciprocated in said compression chamber for creating a vacuum therein for drawing air and oil from said intermediate chamber into said compression chamber during one stroke, and for compressing the mixture in said compression chamber during another stroke, and means for varying the quantity of measured charge transferred. 110 115 120

Signed at Chicago, Illinois, this 28th day of April, 1921.

EZEKIEL FIELD WHITE.
